VORTEX TUBE WITH DIVERGENT HOT END

Willem Pieter Hendaal, Amsterdam, Netherlands, assignor to Shell Development Company, New York, N.Y., a corporation of Delaware

Application June 5, 1956, Serial No. 589,423

Claims priority, application Netherlands June 10, 1955

7 Claims. (Cl. 62—5)

This invention relates to a vortex tube within which a gas stream is expanded with gyratory motion about the tube axis to separate the gas into hot and cold fractions, and from which tube gas is discharged continuously in a manner dependent upon the particular purpose to which the tube is put. Thus, the two gas fractions may be discharged in any desired ratio from zero to infinity; in other words, two gas streams having different temperatures or only one gas stream may be discharged from the tube. The utility of discharging only one stream will become apparent from the sequel. Although not restricted thereto, vortex tubes find particular utility for the production of cold gas streams from gas which occurs initially at superatmospheric pressure, especially when the refrigeration load in a given process wherein the cold gas is to be utilized is so small or intermittent that more elaborate machinery, such as adiabatic expansion engines, are not economically attractive.

The vortex tube, also known as the Ranque tube or Hilsch tube, uses no moving parts and is low in cost. Such a tube was described in U.S. Patent No. 1,952,281 to Ranque, and Hilsch drew further attention to it in articles published in *Zeitschrift für Naturforschung*, vol. 1, pp. 208-214 (Wiesbaden, Germany, 1946) and in *Review of Scientific Instruments*, vol. 18, pp. 108-113 (New York, 1947). A bibliography on vortex tubes, written by Curley and MacGee, Jr., was published in *Refrigerating Engineering*, vol. 59, 1951, pp. 66 and 191-193. As is set out in the said patent and the other publications, the vortex tube includes a vortex chamber having the shape of a body of revolution, such as a cylinder, an inlet for admitting a feed gas under pressure with a gyratory motion, e.g., one or more inlet pipes situated near one end of the tube and disposed tangentially and in the same circumferential direction, and suitable outlet means for discharging one or both of the gas fractions which appear within the tube. These fractions are formed respectively as a peripheral stream in contact with the inner surface of the tube wall and as a core rotating coaxially within the peripheral stream, the former being warmer and the latter being colder than the feed gas. Both fractions have pressures lower than that of the feed gas but the pressure of the fraction having the higher temperature exceeds that of the other fraction, in accordance with the Ranque effect. This phenomenon of the separation of the gas by expansion within the vortex tube into hot and cold fractions is hereinafter referred to as the heat-separation effect. This heat-separation effect results in the heating of at least a part of the vortex tube wall, unless it is extraneously cooled.

The dimensions of such tubes may vary within wide limits according to the conditions under which the tube is to operate; suitable dimensions are readily determined experimentally in accordance with the principles and examples given in the art noted above. Thus, the vortex tube

2

may have a length of 6 to 30 diameters, length of 18 to 20 diameters being common.

Various outlet arrangements are possible. In one common arrangement, the cold gas fraction is discharged through an orifice situated at the tube axis in a plate or end wall near and to one side of the tangential inlet; the vortex tube extends through almost all of its length to the other side of the inlet, and the latter part, also known as the hot end, has a discharge opening for the hot gas fraction, situated either near the periphery or near the axis. By throttling one or the other of the effluent streams, e.g., by the use of a throttling valve at the hot-gas outlet and/or by selecting a cold-gas orifice of suitable size, their ratio and, hence, their temperatures can be varied; typical temperature effects are indicated graphically by Hilsch, op.cit., and by Sprenger, on page 295 of *Zeitschrift für Angewandte Mathematik und Physik*, vol. II (Basel, Switzerland, 1951). Hot gas which travels away from the inlet through the hot end in excess of the amount, if any, which is discharged at the extremity of the hot end flows again with the cold core toward the discharge orifice for the cold gas fraction. By cooling the hot fraction while within the vortex tube, as by applying a coolant to the wall of the hot end of the tube (see German Patent No. 468,487), the volume of gas that can be drawn off as the cold fraction at a given temperature is increased and/or the temperature of the discharged cold fraction can be decreased, and a cooled gas stream is attained even when the hot end of the tube is fully closed, so that all gas is discharged as cold gas; the converse is true when the core of the vortex contains a central heating element, such as a small tube through which a heating fluid is circulated, making it possible to draw off all or most of the gas as hot gas by greatly restricting or completely closing off the central cold-gas orifice. In either case an increased heat-separation within the tubes promotes heat exchange with the extraneous cooling or heating fluid.

Among still other draw-off arrangements, to which the present invention is also applicable, are that using the so-called uniflow principle, in which the outlets for the cold and hot gas fractions are arranged concentrically at or near the extremity of the hot end, and that using an annular opening surrounding the tube axis at either end of the tube as the cold-gas outlet; these are illustrated in the Ranque patent cited above.

In all of the foregoing variants, it is desirable to produce a high degree of heat-separation within the vortex tube, and it is the object of this invention to provide a vortex tube having an improved shape by which this heat-separation is increased.

In summary, according to the invention the vortex tube has a hot end, situated to one side of the gas inlet, which end diverges away from the inlet at an angle between 2° and 6°, preferably between 3° and 4°, and a discharge arrangement of any suitable type, such as those outlined above, is provided so that the gas which is admitted through the inlet with a gyratory motion is separated into hot and cold fractions of which the former moves as a peripheral stream in contact with the inner surface of the diverging part of the tube. This part of the tube may be cooled, as by providing a jacket through which a cooling liquid is passed; although the tube wall and peripheral gas stream may be thereby cooled to below the temperature of the feed gas, they are nevertheless for convenience herein called the hot end and the hot gas fraction, respectively, to distinguish them from other parts of the tube and from the cold gas fraction, which is at a lower temperature.

The invention will be described in detail with reference to the accompanying drawings forming a part of this spec-

ification and illustrating one specific arrangement of the vortex tube by way of example, wherein:

Figure 1 is a longitudinal sectional view of a vortex tube constructed in accordance with the invention;

Figures 2 and 3 are transverse sectional views taken on the correspondingly numbered lines of Figure 1; and

Figure 4 is a graph showing the heat-separating effects achieved by vortex tubes of various shapes.

An understanding of the heat-separation effect is basic to an understanding of the following description and the improved results attained. Accordingly, a summary thereof is presented by way of introduction to the detailed description.

A theoretical explanation of the heat-separation effect is based on the fact that there is evidently a transfer of energy from the gas at the central part of the tube to the gas near the confining wall. This transfer of energy increases the temperature of the outer gas layers leaving the tube as the hot gas fraction, e.g., through the throttle valve, and lowers the temperature of the inner gas layers escaping as the cold gas fraction through the orifice.

Closer examination shows that there is first a transfer of energy caused by the friction between the layers of the rotating gas column which are in the neighbourhood of the tube axis and the layers nearer to the wall of the tube. As the inner layers rotate at a higher angular velocity than the outer layers, the inner layers tend to accelerate the outer ones by friction, the result being a transfer of kinetic energy in a direction outward from the tube axis. A second, more important contribution to the temperature effect is the transfer of energy caused by turbulent currents in the radial pressure field of the rotating gas column. Owing to the strong centrifugal forces there is a considerable difference in pressure between the inner and outer layers. As a result of the said turbulent currents a quantity of gas will move outwards and be compressed more or less adiabatically, as a result of which the temperature of the outer gas will rise. A quantity of gas moving in the opposite direction will expand and become cooler. In this way the turbulence will cause a temperature distribution in a radial direction.

According to this theory, the Ranque effect is governed by three variables, viz.:

(1) The effect is dependent on the absolute temperature (T) of the fed gas introduced.

(2) The effect is dependent on the ratio of the inlet pressure of the feed gas (p_0) to the expansion pressure outside of the tube (p); this pressure ratio

$$\frac{p_0}{p}$$

is hereinafter termed the effective pressure ratio.

(3) The effect is dependent on the ratio between the specific heat at constant pressure (c_p) to that at constant volume (c_v) of the gas used.

In order to compare quantitatively the effect of vortex tubes of different designs, when the tubes in question are used as a cooling apparatus, note is taken of the ratio between the decrease in the enthalpy of the quantity of gas leaving the vortex tube as cold gas and the decrease in the enthalpy which would be theoretically reached when the whole amount of gas were allowed to expand isentropically while carrying out external work. This ratio is hereinafter termed the cooling effect; it may be considered as the efficiency of the vortex tube.

In the case of an ideal or practically ideal gas such as air (wherein the ratio

$$\frac{c_p}{c_v}$$

is constant and there is a very small or no Joule-Thomson effect), the above-mentioned cooling effect or efficiency

5 may be expressed as follows, based on a calculation of this ratio:

$$\eta_r = \frac{\mu \Delta T}{T_0 \left[1 - \left(\frac{p_0}{p} \right)^{\frac{1-k}{k}} \right]}$$

in which:

μ =the separation coefficient, that is, the ratio of the quantity of the cold gas fraction to the total quantity of gas;

ΔT =difference in temperature between the feed gas and the cold gas leaving the vortex tube;

η_r =the cooling effect or efficiency factor of the refrigeration;

T_0 =absolute temperature of the feed gas;

p =expansion pressure outside of the vortex tube;

p_0 =pressure of the feed gas supplied; and

$$k = \frac{c_p}{c_v}$$

$$c_v$$

In Hilsch's experiments, in which the vortex tube had a diameter of 4.6 mm. and a cold-gas orifice of 2.6 mm., a maximum cooling effect correspond to a value of $\mu=0.6$. In this case the quantity η_r had a value of nearly 0.18. In his publications Hilsch observed that the cooling effect was not influenced by any special shape of the vortex tube or of the hot end thereof. Sprenger, op. cit., states on page 297 that the cooling effect is only slightly affected by the shape of the vortex tube and mentions generally, inter alia, divergent and convergent tubes.

Contrary to these earlier opinions, it has now been found that, under conditions which are otherwise comparable, appreciably lower temperatures or a significantly higher heat-separation effect can be obtained by constructing the hot end of the vortex tube with a divergence away from the inlet, provided that the angle of divergence is held between 2° and 6°, preferably between 3° and 4°; outside of these limits only the slight effects noted by prior experimenters are observed. By the angle of divergence is herein meant the apex angle of a cone the surface of which coincides with the divergent part of the tube; this part is frusto-conical and should have a length of at least one diameter thereof, preferably at least four times the initial or smaller diameter thereof.

Referring to Figures 1-3 in detail, the tube may include a tangential inlet nozzle 29 the end 30 of which is advantageously joined to the confining wall of the vortex tube by a spiral wall 31, as shown in Figure 2, so as to center the resulting gas vortex at the axis of the tube. The tube is shaped internally as a surface of revolution, and includes a section 32 which diverges away from the inlet at an angle between 2° and 6°, preferably between 3° and 4°. The wide end of section may be joined smoothly to a cylindrical section 33. The sections 32 and 33 (when provided) constitute the hot end of the tube. An orifice disc 34, mounted near the inlet nozzle, has an orifice 35 situated at the central axis of the vortex tube for the discharge of the cold, central part of the gaseous vortex which constitutes the cold fraction. The latter flows through a short diverging section 36 into a discharge pipe 37. The hot end of the tube may have a convergent section 38 by which the hot fraction is led to a discharge pipe 39 and with a suitable throttling device, such as a valve 40 which is axially reciprocable. The tube is jacketed as shown at 41, whereby a cooling liquid such as water can be circulated through the inlet and discharge nozzles 42 and 43 and in contact with the confining walls of the sections 32 and 33 for cooling these walls intensively. This cools the hot gas fraction, which moves as a peripheral stream within the tube in contact with the confining wall sections. This cooling may be sufficiently intensive to cool the discharged hot gas fraction approximately to or even below the temperature

of the initial gas. Adjustment of the valve 40 permits the ratio of the hot and cold gas fractions to be varied; when the valve is fully shut all entering gas is discharged as cold gas through the orifice 35, but there is nevertheless a separation within the tube whereby a hot gas fraction travels through the hot end, before returning toward the orifice near the central axis of the tube.

Example

The advantages of the construction according to the invention are indicated by the following tests, performed using air in four different vortex tubes, one being cylindrical throughout and the other three having different angles of divergence; these tubes are herein referred to as I, II, III and IV, respectively.

The chief dimensions of the cylindrical vortex tube I were:

Inside diameter	mm	10
Length	do	190
Area of inlet nozzle at 30	sq. cm	6.72
Diameter of discharge orifice 35	mm	6

The diverging vortex tubes II, III and IV had, except for the divergence, the said dimensions as the cylindrical tube; their angles of divergence, 2.9°, 3.6° and 4.8°, respectively, were obtained by using sections 32 which had lengths of 100 mm., 80 mm., and 60 mm., respectively, and complementary lengths of cylindrical sections 33, the latter having an internal diameter of 15 mm.

The vortex tubes were tested under the following conditions:

Pressure of the feed gas, p_0	6 atmos. abs.
Temperature T_0 of the feed gas	519° R. (59° F.)
Rate of air flow	61.7 lbs./hr.
External pressure p	1 atmos. abs.

In these tests various separation coefficients were used for each tube by adjustment of the throttle valve at the hot end outlet. The test results are shown in Figure 4 of the drawing, wherein the cooling effect is plotted against the separation coefficient, the curves being identified with Roman numerals corresponding to the vortex tubes used. The curves show that the optimum cooling effect is obtained with an angle of divergence of about 3.6° and a separation coefficient of 0.65. Compared to the cylindrical vortex tube I, there is a 10% improvement in the cooling effect.

No extraneous wall cooling was used in the foregoing which were practically adiabatic tests. In additional tests with tubes shaped as tubes I and III, above, other conditions remaining unchanged, water at a temperature of 59° was circulated through the jacket 41 which surrounded the hot end of the tube; results for these tests are also shown on Figure 4 by dashed lines marked V and VI, respectively. These curves show a maximum cooling effect for tube VI, having an angle of divergence of 3.6°, when the separation coefficient was 0.80; in this instance there was an improvement in the cooling effect of 15% compared with the cylindrical tube. These results show the peculiar merit of combining the diverging tube with the means for cooling the tube wall.

I claim as my invention:

1. A vortex apparatus for separating a gas stream therein into hot and cold fractions by the heat-separation effect comprising: a chambered body enclosing a tube-shaped vortex chamber at least a part of which diverges with an angle of divergence between 2° and 6° for an axial distance of at least the initial diameter thereof; one or more inlets disposed tangentially to said chamber at the narrower end of said diverging part for admitting said gas stream with a gyroscopic motion and thereby separating said gas into a hot fraction which moves as a peripheral stream through said diverging part and a cold fraction forming a core within said peripheral stream; and means for discharging said gas from the chamber.
15. 2. A vortex apparatus according to claim 1 wherein said angle of divergence is between 3° and 4°.
3. A vortex tube according to claim 1 wherein the said diverging part has a length of at least four times the initial diameter thereof.
20. 4. In combination with the vortex apparatus according to claim 1, means for circulating a cooling medium adjacently to said diverging part of the chamber in heat exchange relation to said peripheral stream for cooling said stream.
25. 5. A vortex tube apparatus according to claim 1 which includes an end wall to said chamber situated near to said inlet and on the side thereof opposite the direction of divergence, and said gas discharge means includes individual outlets for said hot and cold fractions, the former being displaced from the inlet in the direction of divergence by a distance of at least the initial diameter of the diverging part and the latter being a passageway in said end wall situated substantially at the central axis of the chamber and having a diameter less than that of the chamber.
35. 6. A vortex tube for producing cold gas from an initial gas stream under pressure by the heat-separation effect comprising: a tubular body having an interior surface of revolution about an axis; one or more inlets disposed tangentially to said surface and dividing the tube into hot and cold ends situated, respectively, on opposite sides of the inlet, the interior surface of said hot end being empty and divergent in a direction away from the inlet with an angle of divergence between 2° and 6° for a distance of at least the initial diameter thereof; means providing at said cold end a discharge orifice for cold gas; and means for circulating a cooling fluid in heat exchange relation to the outside of the said hot end of the tube.
40. 7. A vortex tube according to claim 6 having a separate outlet for hot gas at the end of the hot end of the tube which is remote from the inlet.
